POTENTIAL CONTROL SYSTEM

Burt S. Burke, Forest Hills, Pa., and Cornelius V. Heck, Elizabeth, N. J., assignors to Westinghouse Electric & Manufacturing Company, East Pittsburgh, Pa., a corporation of Pennsylvania

Application January 25, 1933, Serial No. 653,454

7 Claims. (Cl. 175—312)

Our invention relates, generally, to potential control systems, and, more particularly, to systems for controlling the potential impressed on theatre lighting circuits.

5 In theatre lighting control systems, it is desirable to pre-set the potential that will be applied to the various lighting circuits during each scene of a performance in order that the desired intensity of illumination and the desired 10 color effects may be produced for each scene at the will of the operator. It is also desirable to fade from one lighting effect to another in a smooth manner and it is often necessary to repeat effects, or to flash from one effect to another without passing through a number of intervening effects or scenes.

Present schemes provide for the presetting of intensities and are so arranged that a number of effects may be produced in a predetermined 20 sequence, but all of the present schemes with which we are familiar are limited in their application to a few scenes and do not permit the operator to smoothly fade from one scene to any other scene without passing through the 25 intervening scenes.

An object of our invention, generally stated, is to provide a practical system for controlling a plurality of electric circuits which will be simple and efficient in operation and which may be 30 readily and economically manufactured and installed.

A more specific object of our invention is to provide for pre-setting a plurality of lighting effects and for producing the effects in any desired sequence, either by fading or flashing from one effect to another without passing through any intervening effects.

A further object of our invention is to provide a simple and economical means for pre-setting the potential impressed on a plurality of electric circuits.

Other objects of our invention will be either explained hereinafter, or will be apparent to those skilled in the art.

45 In accordance with one embodiment of our invention a plurality of multi-contact relays are provided for establishing the circuits which control the energization of various theatre lighting circuits. The operation of the relays is controlled by a plurality of push-button switches which are so mechanically interlocked that only one switch will be closed at a time. The contact members of the relays are so connected that, by operating the proper push-button 50 switches, it is possible to either fade from one

lighting effect to another or flash from one effect to another.

For a fuller understanding of the nature and scope of our invention reference may be had to the following detailed description, taken in connection with the accompanying drawings, in which:

Figures 1 and 2 together constitute a diagrammatic view of a control system embodying our 10 invention.

Referring now to the drawings, the illustrated embodiment of our invention comprises two theatre lighting circuits 10 and 11, connected across power conductors 12 and 13 which may be energized from any suitable source of alternating-current power (not shown). In order to simplify the drawings and description only two lighting circuits, with five scenes for each circuit have been illustrated, however, it will be understood that the system illustrated may be 15 readily expanded to control as many circuits and scenes as desired.

The current in the lighting circuits 10 and 11 and, consequently, the intensity of illumination supplied by the lamps 14 and 15, is controlled by 25 saturated-core reactors 16 and 17, respectively. Each of the reactors comprises two alternating-current windings 18, disposed on the outer legs of the reactor and a direct-current control winding 19, disposed on the inner leg. The reactance 30 of each reactor and the current in the lighting circuits may be regulated, in a manner well known in the art, by varying the current in the control winding 19. The current in the control windings 19 of the reactors 16 and 17 may be 35 regulated by varying the grid-biasing potential impressed on electronic-tube amplifying circuits 21 and 22, respectively, as fully described in the copending application of R. D. Ross, Serial No. 450,586, filed May 7, 1930. However, the system herein described is not limited in its application to amplifying circuits of the type disclosed in the foregoing application but may be applied to any electronic-tube amplifying scheme utilizing 40 potential control of the output of the tubes. 45

In order that a pre-selected value of potential may be impressed on the tube circuits 21 and 22 to produce the desired illuminating effects from the lighting circuits 10 and 11 during any scene of a theatrical production, and that the 50 effect may be changed either instantaneously or gradually from one scene to any other scene without passing through intervening scenes we have provided the control system herein described. 55

As stated hereinbefore, the apparatus necessary for controlling two circuits, with five scenes for each circuit has been illustrated. If it is desired to control more circuits or scenes additional equipment, similar to that shown, may be supplied. The apparatus for controlling the potential impressed on the tube units 21 and 22, which in turn control the lighting circuits 10 and 11, comprises two pre-settable potentiometers 23 and 24, each provided with five sliders, one for each of the five scenes which may be set up in advance, individual control potentiometers 25 and 26 by means of which each circuit may be controlled individually, change-over switches 27 and 28 for changing from pre-set to individual control, and two gang-operated potentiometer resistors or faders 29 and 30.

It will be noted that the pre-set potentiometers 23 and 24 are each provided with five sliders which may be set up in advance to impress the proper potential on the tube control units to produce the desired lighting effect for each scene. By placing the five sliders on one potentiometer instead of providing five potentiometers, as has been done previously, a considerable saving is effected in the amount of equipment required for controlling each circuit. The potentiometers may be readily so constructed that the sliders may be operated without mechanical interference.

In order that the operator may change from one scene to any other scene, either instantaneously or gradually, two relays are provided for each scene to be controlled. These relays are designated as 31, 32, 33, 34 and 35, and 31a, 32a, 33a, 34a and 35a. In addition, two relays 36 and 36a are provided for extinguishing or "blacking-out" the lights of each circuit at any time. Each of the foregoing relays is provided with as many sets of contact members as there are circuits to be controlled, which, in this instance is two.

The operation of the relays 31 to 36 and 31a to 36a, inclusive, is controlled by push-button switches 41 to 46 and 41a to 46a, respectively. As shown, the switches 41 to 46 are provided with an interlock bar 40 which is so constructed that only one of the switches will be closed at a time, that is, when any one of the switches is actuated to the closed position any other switch of the group, which has been previously closed, will be automatically released. Likewise, the switches 41a to 46a, which control the operation of the relays 31a to 36a, respectively, are provided with an interlock bar 40a which is so constructed that only one switch may be closed at a time.

A master control potentiometer 47, which is connected across control conductors P and N, may be utilized to obtain group control of all circuits which are connected to it. The change-over switches 48 and 49 are provided for either connecting the pre-set potentiometers directly to the control conductors P and N or to the master potentiometer 47, as desired. Resistors 51 to 55, inclusive, and 51a to 55a, inclusive, are provided to prevent short circuiting the control bus through the contact members of the relays.

In order that the functioning of the apparatus may be better understood, the operation of the system will now be described. Assuming that the switches 27 and 28 are closed in the position shown in the drawing, which provides for pre-set control of the lighting circuits 10 and 11, and that the switches 48 and 49 are closed, as shown, to connect the pre-set potentiometers

23 and 24 across the control conductors P and N, also assuming that the sliders on the potentiometers 23 and 24 have been pre-set to impress the proper potential on the tube units 21 and 22 to produce the desired lighting effects for each of the five scenes, the effect for scene 1, may be produced by actuating the push-button switch 41 to the closed position, thereby establishing an energizing circuit for the actuating coil of the relay 31. This circuit may be traced from conductor 61, which is connected to the positive conductor P by means of conductor 62, through conductor 63, the actuating coil of the relay 31, conductor 64, contact member 65 of the switch 41, and conductor 66 to a conductor 67, which is connected to the negative conductor N through a conductor 68.

When the relay 31 is actuated to its closed position, circuits are established to impress a pre-selected biasing potential upon the grid circuits of the tube units 21 and 22, thereby controlling the current in the lighting circuits 10 and 11, respectively, and producing a predetermined lighting effect, as previously described.

The circuit for impressing a biasing potential on the tube unit 21 extends from the potentiometer 23 through conductor 71, resistor 51, conductors 72 and 73, contact members 74 of the relay 31, conductor 75, the arm 76 of the fader 29, conductor 77, switch 27 and conductor 78 to the tube unit 21.

The circuit for impressing a biasing potential on the tube unit 22 may be traced from the potentiometer 24, through conductor 81, resistor 51a, conductors 82 and 83, contact members 84 of the relay 31, conductor 85, the arm 86 of the fader 30, conductor 87, the switch 28 and conductor 88 to the tube unit 22.

If it is desired to change instantaneously from scene 1 to any other scene, as for example, scene 3, it is only necessary to actuate the push-button switch 43 to the closed position, which automatically releases the switch 41, as previously explained, and also permits the relay 31 to drop to its lowermost position. When the switch 43 is closed, an energizing circuit is established for the actuating coil of the relay 33 which extends from conductor 61, through conductor 89, the actuating coil of the relay 33, conductor 91, contact members 92 of the switch 43, and conductor 93 to the conductor 67.

The closing of the relay 33 establishes circuits for impressing the biasing potentials on the tube units 21 and 22 which have been previously selected by pre-setting the sliders for scene 3 on the potentiometers 23 and 24. The circuit for impressing a potential on the tube unit 21 extends from the potentiometer 23, through conductor 94, the resistor 53, conductors 95 and 96, contact members 97 of the relay 33, conductor 98 to conductor 75 and thence to the tube unit 21 through the circuit previously traced. The circuit for the tube unit 22 may be traced from the potentiometer 24, through conductor 101, resistor 53a, conductors 102 and 103, contact members 104 of the relay 33, conductor 105 to conductor 85 and thence to the tube unit 22 through the circuit previously traced.

However, if it is desired to change gradually from the lighting effect produced for scene 1 to the effect for scene 3, this may be accomplished by first closing the push-button switch 43a and then operating a shaft 106 to move the arms 76 and 86, of the faders 29 and 30, respectively, to the opposite ends of the poten-

- tiometer-resistors of the faders 29 and 30, which gradually changes the biasing potential impressed on the tube circuits from the potential selected for scene 1 to that selected for scene 3.
- 5 It will be noted that the switch 41 is not released when the switch 43a is closed, therefore, the conductors 71 and 81 remain connected to one terminal of the faders 29 and 30, respectively.
- 10 When the switch 43a is closed, an energizing circuit is established for the actuating coil of the relay 33a, which may be traced from the conductor 61, through conductor 106, the coil of the relay 33a, conductor 107, contact members 108 on the switch 43a, and conductor 109 to the conductor 67. The closing of the relay 33a connects the conductors 94 and 101 to the faders 29 and 30, respectively. The circuit to the fader 29 may be traced from the conductor 94, through 15 the resistor 53, conductors 95 and 96, contact members 111 of the relay 33a, and conductors 112 and 113 to one terminal of the fader 29. The circuit to the fader 30 extends from conductor 101, through resistor 53a, conductors 102 and 25 103, contact members 114 of the relay 33a, and conductors 115 and 116 to one terminal of the fader 30.

After the relay 33a is closed the shaft 106 may be operated to move the arms 76 and 86, of the 30 faders 29 and 30, to the opposite ends of the faders from those shown, thereby gradually changing the biasing potential impressed on the tube units 21 and 22 from the potential selected for scene 1 to that selected for scene 3. In this 35 manner the lighting effect produced by the circuits 10 and 11 may be gradually changed from scene 1 to scene 3 without passing through intervening scene 2.

In a similar manner the operator may change 40 from one scene to any other scene, either instantaneously or gradually, by actuating the proper push-button and operating the faders 29 and 30. For example, if it is next desired to flash from scene 3 to scene 5, the switch 45a 45 may be closed, which will release the switch 43a and the relay 33a and close the relay 35a, thereby immediately impressing the potential selected for scene 5 on the tube circuits 21 and 22 and controlling the current in the lighting circuits 10 and 11, accordingly. Or if it is desired to fade 50 from scene 3 to scene 5, the push-button switch 45 may be closed and the arms 76 and 86, of the faders 29 and 30, respectively, moved back to the 55 positions shown on the drawings, thereby gradually changing the biasing potential impressed on the tube circuits from the potential selected for scene 3 to that selected for scene 5.

If it is desired to "black-out" the lights at any 60 time, either the switch 46 or 46a, depending upon the position of the arms 76 and 86 of the faders 29 and 30, may be closed. If the fader arms are in the position shown in the drawings, the switch 46 should be closed, and if the fader arms are at the opposite ends of the resistors, the switch 46a 65 should be closed in order to "black-out" the lights.

Assuming that the fader arms 76 and 86 are in the position shown, closing the switch 46 will 70 release any other of the switches of its group that may be closed and establish an energizing circuit for the actuating coil of the relay 36. This circuit may be traced from the conductor 61, through conductor 117, the coil of the relay 36, conductor 118, contact members 119 of the 75 switch 46, and conductor 121 to the conductor 67.

When the relay 36 is closed the tube units 21 and 22 are connected directly to the negative conductor N, thereby impressing a negative biasing potential on the tubes which will cause the lights in the circuits 10 and 11 to be extinguished. 5 The circuit to the tube unit 21 extends from the negative conductor N, through conductors 122 and 123, contact members 124 of the relay 36, and conductors 125 and 75 to the tube unit 21 through the circuit previously traced. The circuit to the tube unit 22 may be traced from the negative conductor N, through conductors 126 and 127, contact members 128 of the relay 36, and conductors 129 and 85 to the tube unit 22 through the circuit previously traced. 10 15

In case the fader arms 76 and 86 are at the opposite ends of the resistors from that shown, a negative biasing potential may be impressed on the tube units 21 and 22 to "black-out" the lights in the circuits 10 and 11 by closing the push- 20 button switch 46a which closes the relay 36a by means of an energizing circuit which extends from conductor 61, through conductor 131, the actuating coil of the relay 36a, conductor 132, contact members 133 of the switch 46a and conductor 134 to the conductor 67. 25

When the relay 36a is closed the tube units 21 and 22 are both directly connected to the negative bus N. The circuit for the tube unit 21 may be traced from the negative bus N, through 30 conductors 122 and 123, contact members 135 of the relay 36a, conductor 113, the fader arm 76, conductor 77, switch 27 and conductor 78 to the tube unit 21. The circuit for the tube unit 22 may be traced from the negative conductor N, through conductors 126 and 127, contact 35 members 136 of the relay 36a, conductor 116, the fader arm 86, conductor 87, switch 28, and conductor 88 to the tube unit 22.

As previously stated, the potentiometers 25 and 40 26 are provided to permit either of the lighting circuits to be controlled independently of the other circuit. The circuit 10 may be independently controlled by actuating the switch 27 to connect the conductor 78 to a conductor 137, 45 thereby connecting the tube unit 21 to the potentiometer 25. Likewise, the circuit 11 may be independently controlled by actuating the switch 28 to connect the conductor 88 to a conductor 138, which will connect the tube unit 22 to the 50 potentiometer 26. The slider on the potentiometer 26 may be set at a position which will impress a potential on the tube circuit that will produce the desired intensity of illumination 55 from the lighting circuit.

From the foregoing description, it is apparent that we have provided a novel control system that is suitable for controlling the lighting effects produced by a plurality of circuits. Furthermore, the effect which is to be produced during each scene of a theatrical performance may be set up in advance and produced in any desired sequence either by fading or flashing from one effect to another without passing through several intervening effects or scenes. The system herein 60 described is simple and flexible in operation and may be readily expanded to provide for controlling any desired number of lighting circuits and scenes. 65

We do not desire to be restricted to the particular form or arrangement of parts herein shown and described, since it is evident that they may be changed and modified without departing from the spirit and scope of our invention as defined in the appended claims. 70 75

We claim as our invention:

1. In a system for controlling the potential impressed on an electrical circuit, in combination, a source of electric potential, means for preselecting values of potential to be impressed on said circuit, relay means for impressing a preselected value of potential on said circuit, and means for controlling the operation of the relays to instantaneously change the potential impressed on said circuit from one preselected value to any other preselected value.
2. In a system for controlling the potential impressed on an electrical circuit, in combination, a source of electric potential, means for preselecting values of potential to be impressed on said circuit, relay means for impressing a preselected value of potential on said circuit, and manually-operable interlocked switches for controlling the operation of the relays to instantaneously change the potential impressed on said circuit from one preselected value to any other preselected value.
3. In a system for controlling the potential impressed on an electrical circuit, in combination, a source of electric potential, means for preselecting values of potential to be impressed on said circuit, relay means for impressing a preselected value of potential on said circuit, manually-operable interlocked switches for controlling the operation of said relays, and means cooperating with the relays to gradually change the potential impressed on said circuit from one preselected value to any other preselected value.
4. In a system for controlling the potential impressed on a plurality of electrical circuits, in combination, a source of electric potential, means for preselecting values of potential to be impressed on each circuit, a plurality of multi-contact relays for impressing a selected value of potential on the circuits, each relay having a set of contact members for each circuit to be controlled, and manually-operable interlocked switches for controlling the operation of said relays.
5. In a system for controlling the potential im-

pressed on an electrical circuit during a series of scenes of a theatrical performance, in combination, a source of electrical potential, means for preselecting the value of potential to be impressed on said circuit during each of said scenes, means for selectively making an abrupt or a gradual change in the potential impressed on said circuit from the preselected potential for one scene to the preselected potential for any other non-consecutive scene, and switching means having 10 mutually interlocked contact members for controlling the operation of the last-named means.

6. In a system for controlling the potential impressed on an electrical circuit during a series of scenes of a theatrical performance, in combination, a source of electrical potential, a single potentiometer for preselecting the value of potential to be impressed on said circuit during each of said scenes, means for selectively making an abrupt or a gradual change in the potential impressed on said circuit from the preselected potential for one scene to the preselected potential for any other non-consecutive scene, and switching means having 15 mutually interlocked contact members for controlling the operation 20 of the last-named means.

7. In a system for controlling the potential impressed on an electrical circuit during a series of scenes of a theatrical performance, in combination, a source of electrical potential, a potentiometer connected across said source, a plurality of sliders disposed on the potentiometer for preselecting the value of potential to be impressed on said circuit during each of said scenes, means 25 for selectively making an abrupt or a gradual change in the potential impressed on said circuit from the preselected potential for one scene to the preselected potential for any other non-consecutive scene and manually-operable switching means having 30 mutually interlocked contact members for controlling the operation 40 of the last-named means.

BURT S. BURKE.

CORNELIUS V. HECK. 45
